UNITED STATES PATENT OFFICE.

ARTHUR SMITH CROSBY, OF MARLAND, OKLAHOMA, ASSIGNOR OF TWO-THIRDS TO AMERICAN IRON & MACHINE WORKS, INC., OF TONKAWA, OKLAHOMA, A CORPORATION OF OKLAHOMA.

PARAFFIN CLEANER.

Application filed September 30, 1924. Serial No. 740,782.

To all whom it may concern:

Be it known that I, ARTHUR SMITH CROSBY, citizen of the United States, residing at Marland, in the county of Noble and State 5 of Oklahoma, have invented certain new and useful Improvements in Paraffin Cleaners, of which the following is a specification, reference being had to the accompanying drawings.

10 This invention relates to certain improvements in paraffin cleaners and it is an object of the invention to provide a novel and improved device of this general character especially designed and adapted for use in 15 the cleaning of paraffin which may accumulate on the tubing or casing of an oil well.

Another object of the invention is to provide a novel and improved device of this general character comprising an elongated 20 member having wings pivotally connected thereto whereby said wings automatically close when the tool is being lowered into a well and opened to full size when the tool is raised and operating to clean paraffin or 25 other foreign matter which may have accumulated on the well tubing or casing.

The invention consists in the details of construction and in the combination and arrangement of the several parts of my 30 improved paraffin cleaner whereby certain important advantages are attained and the device rendered simpler, less expensive and otherwise more convenient and advantageous for use, as will be hereinafter more 35 fully set forth.

The novel features of my invention will hereinafter be definitely claimed.

In order that my invention may be the better understood, I will now proceed to describe the same with reference to the accompanying drawings, wherein:—

Figure 1 is a view in perspective illustrating a paraffin cleaner constructed in accordance with an embodiment of my invention; 45 Figure 2 is an enlarged fragmentary view partly in elevation and partly in section of the device as herein disclosed with the wings in extended position;

Figure 3 is a view similar to Figure 2 50 showing the wings in closed position.

As herein disclosed, the cleaner comprises an elongated member or rod M of requisite dimensions and having one end portion threaded, as at 1, for connection with the

tools or rods generally used in cleaning 55 wells. The square portion 2 immediately below the threaded portion 1 is to facilitate the proper application of a wrench or kindred tool to break joint. The central portion of the member M and also at the lower end portion thereof is provided therethrough with an opening 3, the lower or bottom wall 4 of which being straight and substantially at right angles to the longitudinal axis of the member M. The upper wall of 60 the member M at opposite sides of its center is disposed on the reversed bevels or inclines 5 and the portion of the member M through which each of said openings 3 is disposed is reduced in thickness as is clearly 65 illustrated in Figures 2 and 3 of the drawings.

Extending inwardly through the opposite 70 end portions of each of the openings 3 is an arm or lug 6 carried by the central portion of a scraping wing 7, said lugs having their inner or inserted end portions arranged side by side and pivotally engaged with the holding member 8, such as a rivet or the like disposed through the member 75 M and the inner or inserted end portions of the arms or lugs 6.

Each of the wings 7 is substantially semi-circular in form and of a radius to extend beyond the periphery of the member M 80 when in their lowermost position, said position being maintained upon upward movement of the member M within a well tubing or casing by contact with the bottom wall 4 of the coacting opening 3. However, when the member M is lowered within such tubing or casing the wings 7 will swing upwardly as illustrated in Figure 3 so that the member may be readily dropped within the 85 casing.

As the member M is moved upwardly and the wings 7 are extended said wings will contact with the inner walls of the tubing or casing and operate effectively to scrape therefrom paraffin or other foreign matter which may have accumulated on such walls.

As is particularly illustrated in Figure 1 100 the extremities of each of the wings 7 are gradually decreased in thickness from above, as at 9, so that each pair of wings 7 105 will have effective swinging movement without hindrance or obstruction being offered by one of said wings to the other.

From the foregoing description it is thought to be obvious that a paraffin cleaner constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A scraper for a tubing or casing of an oil well comprising an elongated member provided with attaching means and having an opening therethrough, the bottom wall of said opening being substantially at right angles to the longitudinal axis of the member, the top wall having its end portions reversely beveled, scraping wings arranged at opposite sides of the member and provided with inwardly disposed arms extending within the opening, and means for pivotally connecting the inserted end portions of said arms with the member for free swinging movement.
2. A scraper for a tubing or casing of an oil well comprising an elongated member provided with attaching means and having an opening therethrough, the bottom wall of said opening being substantially at right angles to the longitudinal axis of the member, the top wall having its end portions reversely beveled, scraping wings arranged at opposite sides of the member and provided with inwardly disposed arms extending within the opening, and means

for pivotally connecting the inserted end portions of said arms with the member for free swinging movement, the portion of the member through which the opening is disposed being reduced in thickness.

3. A scraper for a tubing or casing of an oil well comprising an elongated member provided with attaching means and having an opening therethrough, the bottom wall of said opening being substantially at right angles to the longitudinal axis of the member, the top wall having its end portions reversely beveled, scraping wings arranged at opposite sides of the member and provided with inwardly disposed arms extending within the opening, and means for pivotally connecting the inserted end portions of said arms with the member for free swinging movement, the extremities of the wings being reduced in thickness from above.

4. A scraper for a tubing or casing of an oil well comprising an elongated member provided with attaching means and having an opening therethrough, the bottom wall of said opening being substantially at right angles to the longitudinal axis of the member, the top wall having its end portions reversely beveled, scraping wings arranged at opposite sides of the member and provided with inwardly disposed arms extending within the opening, and means for pivotally connecting the inserted end portions of said arms with the member for free swinging movement, said scraping wings being substantially semi-circular in form and substantially surrounding the elongated member when in their lowermost positions.

In testimony whereof I hereunto affix my signature.

ARTHUR SMITH CROSBY.
